CLAIM

The ornamental design for a baby lounger, as shown and described.

DESCRIPTION

FIG. 1. is a perspective view of baby lounger components showing the design;
FIG. 2. is a second perspective view thereof;
FIG. 3. is a front elevation view thereof;
FIG. 4. is a rear elevation view thereof;
FIG. 5. is a left side elevation view thereof;
FIG. 6. is a right side elevation view thereof;
FIG. 7. is a top plan view thereof;
FIG. 8. is a bottom plan view thereof;
FIG. 9. is an assembled view of the baby lounger; and,
FIG. 10. is an assembled, folded view of the baby lounger.
Dotted lines show structural features of the baby lounger, and do not represent elements of the claimed design.

1 Claim, 10 Drawing Sheets
